UNITED STATES PATENT OFFICE

2,538,477

MINE CAR SAFETY DEVICE

Earl H. Smith, Royalton, Ill.

Application September 23, 1949, Serial No. 117,456

7 Claims. (Cl. 188—44)

1

This invention relates to new and useful improvements in mine cars and the primary object of the present invention is to provide a mine car attachment to be used in conjunction with the towing means with a mine car so that the mine car will be held against backward movement as the towing means become slack or detached from the mine car as the latter is moving up grade.

Another important object of the present invention is to provide a mine car safety device including pairs of rail gripping members that will always underlie the balls of the rails for a mine car so as to prevent lifting of either the forward or rear ends of mine car relative to its supporting rails.

A further object of the present invention is to provide a mine car safety device including an operating linkage for moving pairs of rail gripping members into or out of clamping engagement with rails, a means for preventing actuation of the linkage when the mine car is traveling on relatively flat, horizontal track, and a rail attachment for actuating said means to block the operation of the linkage as the car approaches a horizontal track but which will also actuate said means to permit operation of the linkage should a car move rearwardly upon a horizontal track and toward a downwardly sloping track section.

A still further aim of the present invention is to provide a mine car safety device of the aforementioned character that is simple and practical in construction, strong and reliable in use, small and compact in structure, efficient and durable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming a part hereof, wherein like numerals refer to like parts throughout, and in which—

Figure 1 is a fragmentary top plan view of a mine car and showing the present invention applied thereon;

Figure 2 is a longitudinal vertical sectional view taken substantially on the plane of section line 2—2 of Figure 1;

Figure 3 is an end view taken substantially in the direction of arrow numbered 3 in Figure 1;

Figure 4 is an enlarged sectional view of Figure 3 and taken substantially on the plane of section line 4—4 of Figure 3;

Figure 5 is a vertical sectional view showing a mine car approaching a horizontal track section

2

from a sloping track section and illustrating the linkage stop members and the operator therefor;

Figure 6 is an enlarged detail sectional view showing the locking or holding means for the linkage stop member; and

Figure 7 is a plan view of a track section that is movable to a position, shown in dotted lines, to permit the present invention to be engaged with the rails for a mine car.

10 Referring now to the drawings in detail, wherein for the purpose of illustration, there is disclosed a preferred embodiment of the present invention, the numeral 10 represents a mine car that is movable on rails 12. Brackets or ears 14 depend from the forward end portion of the car 10 and support a shaft 15 that extends through the leg portions of a, preferably angle iron, U-shaped frame member 16. The web portion of the U-shaped frame 16 is disposed between the car 10 and the leg portions of the frame 16 are suitably fixed between a pair of spaced parallel transverse plates or beams 18.

20 Inner and outer pairs of vertical pins or rods 20 and 22 are journaled for rotation in suitable 25 openings provided in the beams 18 and support circular rail gripping members 24 at their lower ends. The outer circular edges of the members 24 are toothed to effectively grip a rail and the upper and lower faces of the members slope 30 toward each other diametrically so that the members 24 will be wedge shaped in cross section as shown in Figure 5.

35 The members 24 are constructed from an especially high grade of metal to increase the durability and strength of the same. The members 24 are so positioned that their parts having the greatest thickness will engage the rails due to their eccentric mounting on the rods 20 and 22.

An operating linkage is associated with the 40 rods 20 and 22 to move the members 24 into or out of clamping engagement with the rails. This linkage comprises a pair of arms 26 and 28 that are pivoted adjacent their rear ends to the upper ends of the inner pair of rods 20 and 22.

45 Links 30 are fixed to and project laterally from the upper ends of the outer pair of rods 22 and are connected to the rear ends of the arms 26 and 28 by pitmans 32 so that as the forward ends of the arms 26 and 28 are moved rearwardly the rods 20 and 22 will rotate to move the members 24 into clamping engagement with the rails whereas a forward movement of the forward ends of the arms 26 and 28 will rotate the rods 20 and 22 to move the members 24 out of clamping engagement with the rails.

The forward ends of the arms 26, 28 are pivotally secured to the forward bifurcated ends 34 of a pair of rods 36. The rear ends of the rods 36 are connected by a plate or bar 38 that engages the forward end of an elongated resilient member or coil spring 40. The rear end of the coil spring 40 is adjustably secured to the web portion of the frame member 16 and the coil spring 40 yieldingly urges the rods 36 and the forward ends of the arms 26, 28 rearwardly to force the members 24 into clamping engagement with the rails.

Between the beams 18, and disposed transversely of the beams and intermediate the ends of the beams, there is fixed a tubular guide 42 that slidably receives a towing means or rope 44, the latter being secured to the plate 38.

Attention is directed to Figure 7, wherein there is disclosed the manner in which the present invention is applied to the rails 12. The tracks are composed of two rails or rail sections 46 and 48 that are pivoted, as at 50, and which sections are connected by a cross member 52. A pull or the cross member 52 will pivot the sections outwardly to permit the members 24 to be slid under the balls of the rails 12. This operation is necessary since the members 24 are to underlie the balls of the rails at all times regardless as to whether or not the members 24 are engaged with the surface of rails so as to prevent the forward end of the car 10 from rising relative to the rails.

Means is provided to prevent movement of the linkage 26, 28, 36, 32 and thereby restricting the rotation of the rods 20, 22. This means consists of a pair of vertically slidable stop members 54 each of which includes a shank or bar 56 and a beveled disk 58 that is suitably fixed to the lower end of the bar 56. The shanks 56 are slidably received in openings 68 in the beams 18 and are further received in guide sleeves 62 fixed between the beams 18. The stop members 54 are positioned so as to prevent rearward swinging movement of the forward ends of the arms 26, 28.

A holding or locking means is associated with each of the members 54 to hold the same in either a raised or lowered position. This holding means consists of a hollow bolts 64 threaded on the sleeve 62. Springs 66 housed in the interior of the bolts 64 urge locking balls 68 in either upper openings 70 or lower openings 72 provided in the shanks 56.

The stop members 54 are required since when the car 10 is pulled along a flat or horizontal track, slack develops in the rope 44 which would tend to actuate the operating linkage for the member 24. Therefore, when the members 54 are held raised, the locking balls 68 in the recesses 72, the arms 26, 28 are prevented from moving to rotate the members 24 to their rail gripping position.

An operating means for the stop members 54 are provided so that as the car moves from an up slope to a horizontal track, as shown in Figure 5, the stop members 54 will be raised to make the operating linkage for the members 24 inoperative. This latest means comprises a pair of rail attachments or brackets 74 that are secured to the rails 12, and more particularly at the beginning of a flat or horizontal track section. The brackets 74 include forwardly and upwardly inclined, resilient, arms 76 upon which the disks 58 ride as the car 10 is pulled forwardly. The forward extremities of the arms 76 will flex as the disk 58 rides thereon so that an accidental or intentional rearward movement of the car 10, after

it has passed the brackets 74, will cause the disks 58 to slide beneath the forward extremities of the arms 76 to urge the stop members 24 downwardly where the linkage 26, 28, 30, 32 can actuate the members 24 to their rail gripping position.

In view of the foregoing description taken in conjunction with the accompanying drawings it is believed that a clear understanding of the operation, construction and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Obviously, the outer peripheral edges of the gripping members or cams 24 may be smooth or provided with circumferentially spaced gripping teeth in order to increase the efficiency of the members 24 in gripping the surface of the rails.

Having described the invention, what is claimed 25 as new is:

1. A mine car safety device comprising pairs of rail gripping members, an operating linkage for selectively urging said members into and out of clamping engagement with a rail, a pull rope connected to said linkage and urging said members out of clamping engagement with a rail upon a pull of the rope, means yieldingly urging said members into clamping engagement with a rail, and a means for preventing actuation of the linkage when a mine car is disposed on a relatively flat track section and there is slack in the rope.

2. The combination of claim 1 wherein said means for preventing actuation of the linkage includes a vertically movable stop member, and a rail attachment for slidably engaging the stop member to direct the latter to a position for blocking movement of said linkage.

3. The combination of claim 2 wherein said rail attachment is an elongated resilient arm having first and second portions, the first end portion of said arm engaging and urging said stop member to a position for blocking movement of said linkage upon movement of the car in one direction and the second end portion of said arm urging the stop member to a position to permit actuation of said linkage upon movement of the car in an opposite direction.

4. In a mine car, a safety attachment for the mine car to prevent rearward movement of the car on its rails, said attachment comprising first and second pairs of rail gripping members, an operating linkage for selectively urging the members into and out of clamping engagement with the rails for the car, a towing means for the car, said towing means being connected to the linkage for urging the members out of clamping engagement with the rails for the car upon a pull on the towing means, a means connected to the linkage for forcing the members into clamping engagement with the rails for the car upon slack in the towing means, means associated with and disposed adjacent the linkage for preventing operation of the linkage when the car is disposed on a relatively flat track section, and means mountable on the rails for operating said last mentioned means.

5. The combination of claim 4 wherein said means for preventing operation of said linkage includes a vertically slidable stop member, said

means for selectively holding the stop member in a raised position for blocking operation of the linkage and a lowered position permitting operation of the linkage.

6. The combination of claim 5 wherein said means for holding the stop member in a raised or lowered position includes a spring urged locking ball, said stop member having upper and lower recesses for selectively receiving said locking ball.

7. The combination of claim 4 wherein said means connected to the linkage for forcing the members into clamping engagement with the rails for the car includes rods connected to said linkage, a bar connecting said rods, and a spring member secured to said bar and urging said bar 15

and said rods to a position for moving the linkage and forcing the pairs of members into clamping engagement with the rails for the car.
